(57) **CLAIM**

The ornamental design for a vaping device, as shown and described.

DESCRIPTION

FIG. 1 is an upper perspective view of the vaping device showing my design in an assembled configuration;

FIG. 2 is a front elevation view thereof;

FIG. 3 is a back elevation view thereof;

FIG. 4 is a side elevation view thereof;

FIG. 5 is an opposite side elevation view thereof;

FIG. 6 is a top plan view thereof;

FIG. 7 is a bottom plan view thereof;

FIG. 8 is another upper perspective view thereof in an exploded configuration for a cartridge, shaft, and charger of the vaping device;

FIG. 9 is still another upper perspective view thereof in a partially exploded configuration for the cartridge and the shaft separated from the charger;

FIG. 10 is an upper perspective view of the charger of the vaping device;

FIG. 11 is a front elevation view of the charger;

FIG. 12 is a back elevation view of the charger;

FIG. 13 is a side elevation view of the charger;

FIG. 14 is an opposite side elevation view of the charger;

FIG. 15 is a top plan view of the charger;

FIG. 16 is a bottom plan view of the charger;

FIG. 17 is an upper perspective view of the shaft of the vaping device;

FIG. 18 is a front elevation view of the shaft;

FIG. 19 is a back elevation view of the shaft;

FIG. 20 is a side elevation view of the shaft;

FIG. 21 is an opposite side elevation view of the shaft;

FIG. 22 is a top plan view of the shaft;

FIG. 23 is a bottom plan view of the shaft;

FIG. 24 is an upper perspective view of the cartridge of the vaping device;

FIG. 25 is a front elevation view of the cartridge;

FIG. 26 is a back elevation view of the cartridge;

FIG. 27 is a side elevation view of the cartridge;

FIG. 28 is an opposite side elevation view of the cartridge;

FIG. 29 is a top plan view of the cartridge; and,

FIG. 30 is a bottom plan view of the cartridge.

The broken lines in the drawings represent unclaimed environmental subject matter and form no part of the claimed design.
